TROUSER SHIELD

Filed Nov. 7, 1925

FIG. 1.

FIG. 2.

FIG. 3.

Inventor
Charles S. Knapp

By Milo B. Stevens & Co.

Attorneys

UNITED STATES PATENT OFFICE.

CHARLES SUMNER KNAPP, OF NATIONAL CITY, CALIFORNIA.

TROUSER SHIELD.

Application filed November 7, 1925. Serial No. 67,650.

My invention relates to cuff protectors for trousers and is particularly designed to prevent the bottom edge of the cuff from becoming frayed or worn from contact with 5 the heel of the shoe.

Several important objects of the invention are, to provide an improved device of this character which can be permanently attached to the cuff in concealed position with- 10 out injury thereto; one which will not detract from the appearance of the trousers; and further which will not interfere in any way with the pressing or hanging of the trousers.

15 Other objects will become apparent as the description proceeds.

In the drawing forming a part of this specification,

20 Figure 1 is a cross section through a trouser cuff showing the device applied and showing a portion of a shoe in elevation;

Figure 2 is a section on the line 2—2 of Figure 1;

25 Figure 3 is a section on the line 3—3 of Figure 2, and

Figure 4 is a perspective view of the device.

Referring specifically to the drawing, 30 designates a rectangular strip of leather which is preferably of the kind commercially known as "pantesote" and which is impervious to moisture.

Two thin flat metal plates 4, substantially narrower than leather strip 3 and about 35 half as long, are riveted as at 5, or otherwise securely fastened to strip 3 with their opposed inner ends spaced from each other as clearly shown in Figure 4 whereby said plates are hingedly connected. Figure 4 also clearly shows that the outer end of each 40 plate 4 extends beyond the adjacent end of the strip 3, and further that the corresponding longitudinal edges of plates 4 are contiguous with one longitudinal edge of strip 3.

45 In use the device is applied inside the back of a trouser cuff 6 with the intermediate hinge portion of strip 3 exactly centered or aligned with the cuff crease. The plates 4 are disposed against the hem of the 50 cuff with the contiguous edges of the parts 3 and 4 substantially flush with the lower edge of the cuff. The device is secured in place by stitching the upper portion of strip 3 to the cuff hem as at 7. Also by stitching 55 through the holes 4^a in the projecting ends

of plates 4 and into the cuff hem, which latter prevents plates 4 from partaking of any substantial swinging movement away from inner cuff surface. This also obviates the necessity of a fastening expedient at the 60 cuff edge which would tend to weaken cuff and cause fraying. It is desired to particularly emphasize the fact that the upper portion of the strip 4 which is attached to the cuff hem, and the apertured ends of plates 4 65 are positioned beyond the area which is subjected to the wear of the shoe heel. Thus, continued use of the device will not cause the stitching to wear through.

As will be readily appreciated the usual 70 wear of the shoe heel against the cuff edge is taken by the strip 3 and the lower edge thereof is prevented from wearing away by reason of the fact that strip 3 is reinforced by plates 4 the lower edges of which 75 are flush or contiguous with the edge of the cuff and edge of strip 3.

I claim:

1. A cuff protector comprising a substantially rectangular strip of flexible material, 80 a pair of metal plates relatively narrower than said strip and secured thereto, one longitudinal edge of each of said plates being contiguous with the lower edge of said strip, and the inner ends of said plates being 85 spaced whereby the portion of said strip between the ends of said plates constitutes a hinge for connecting the same, and the upper edge of said strip beyond said plates being adapted to be fastened to the cuff hem to 90 position the lower contiguous edges of the strip and plates substantially flush with the lower edge of the cuff and to dispose the cuff crease intermediate the inner ends of the plates.

2. A cuff protector comprising a substantially rectangular strip of flexible material, 95 a pair of relatively stiff wear resisting plates secured to said strip, the inner ends of said plates being spaced whereby the intermediate strip portion constitutes a hinge for permitting relative swinging movement of said plates, one longitudinal edge of each of said plates being contiguous with a common longitudinal edge of said strip and the outer ends of said plates extending beyond the outer ends of said strip and having means 100 for attachment to the cuff, and said plates being relatively narrower than said strip whereby the upper longitudinal portion 105 110

thereof defines a cuff attaching portion whereby the device may be positioned at the rear of a trouser cuff hem with the contiguous edges of said plates and strip substantially flush with the lower edge of the cuff with the plates on either side of the cuff crease, the cuff attaching means at

the ends of said plates retaining the device in substantially flat contact with the cuff hem, and both of said attaching means being 10 beyond the area of said cuff which is subjected to wear from the shoe heel.

CHARLES SUMNER KNAPP.
